UNITED STATES PATENT OFFICE.

ARTHUR L. LERCH, OF LOCKPORT, NEW YORK.

MOP-PRESS.

1,246,956.

Specification of Letters Patent. Patented Nov. 20, 1917.

Application filed May 6, 1914. Serial No. 836,762.

To all whom it may concern:

Be it known that I, ARTHUR L. LERCH, a citizen of the United States, residing at Lockport, N. Y., in the county of Niagara and State of New York, have invented certain new and useful Improvements in Mop-Presses, of which the following is a specification, reference being had therein to the accompanying drawing.

10 This invention relates to mop wringers or mop pressing structures, and more especially to those adapted to be mounted upon the inside of a pail, bucket, or like receptacle.

15 The object of the invention is to provide a strong and convenient but comparatively inexpensive mop-press having walls provided with a series of perforations or apertures so disposed and formed that the mop 20 cannot be forced into said perforations and become caught therein during the pressure imposed thereon to force the water from the mop.

Another object within the contemplation 25 of this invention is to construct a mop-press in such manner that not only will it be effective in connection with mops of different sizes; but, while being used, produces no wear or tear upon the mop by reason of 30 the structure having perforations or apertures of effectual dimensions, and the walls of which are so formed as to produce a compressing action upon the strands of the mop when the same is moved with pressure to- 35 ward the bottom of the vessel.

A further object of the invention is to provide such a press with means for conveniently attaching or otherwise mounting it upon the side of a bucket or the like and 40 for maintaining it in a substantially perpendicular position in relation to the walls of the bucket.

Other objects and advantages will be in part obvious from the annexed drawings, 45 and will also in part be pointed out in the following description.

The invention resides broadly in the features of construction, the combination of elements, aggroupment and arrangement of 50 parts, and in the details thereof, all as will be exemplified in the structure hereinafter set forth, and the scope of application of which will be indicated in the claims hereto appended.

55 In order that the invention may be more readily understood by those skilled in the

art, I have in the appended drawings— which form a part hereof—illustrated by way of example, two of the embodiments and utilizations of the invention which I have devised.

In these drawings:

Figure 1 is a view in perspective of a mop-press constructed in accordance with my invention; the same in this instance being 65 shown as unattached to a bucket;

Fig. 2 is a view in rear elevation showing the same mounted upon a bucket, the latter being shown in somewhat fragmentary form and as partly broken away adjacent the portion at which the press is attached thereto;

Fig. 3 is a fragmentary view in top plan thereof;

Fig. 4 is also a fragmentary view, in side elevation, showing the general form of the 75 upper portions of the press and, also, the press-attaching device in locked position;

Fig. 5 is a fragmentary view, in vertical section, of a portion of one of the perforated walls of the press.

80 Referring to these drawings, the reference-character 1 designates, generally, the mop-press-vessel, the same being shown (in the embodiment illustrated in Figs. 1 to 5) as including a front-portion or wall 2; a rear-portion or wall 3; two end-portions or walls 4, and a bottom 5. The vessel may be formed from a single piece of suitable metal, appropriately stamped out and the several portions secured together, in any preferred manner; or the several portions may be separately formed and then secured together.

95 The front and rear walls, for the greater portion of their height, are preferably arranged approximately parallel; but, adjacent their upper ends they are bent or curved outwardly and away from each other whereby the space between them at the top is of greater dimensional area than farther down. This presents a flaring entrance into the vessel for the more convenient and ready introduction of the mop out of which the water is to be pressed. The upper extremity 100 6 of the rear wall 3 is relatively higher than the upper extremity 7 of the front wall 2 and extends rearwardly (in a curve) considerably beyond the plane of the walls of the body-portion of the rear wall, as clearly shown in Fig. 4. The upper extremities 8 105 of the end-walls 4 are also flared outwardly, as shown in Figs. 1 and 2.

The front and rear walls and the bottom are provided with a series of escape-perforations or apertures 9 which are preferably round (though they could be of other 5 shape) and are so formed as to have their mouths or outer edges 10 projected considerably beyond the plane of the outside surface of the wall, as particularly shown in Fig. 5. The walls which terminate in these 10 apertures are in form substantially truncated cones. This peculiar formation of these apertures is a feature of my invention, and it subserves the function of permitting the free passage therethrough of the water 15 but without danger of parts of the mop being forced all the way through the apertures or their becoming caught therein. Moreover, the walls of the apertures compress those strands of the mop which are forced 20 into them; and this greatly aids in pressing out the water. The inside surfaces of the walls will be relatively smooth, that is, there will be presented to the mop no rough surface. It is, therefore, a desideratum of my 25 invention so to construct the device that when the mop is inserted into the vessel, the former may be pushed down toward its bottom and there will be no rough edges or burs presented at the escape-openings to 30 tear or catch the mass of strands of which the mop may be formed.

Preferably and as shown, these escape-apertures are formed in the walls only part way up. This leaves an effective portion or 35 surface of each wall to exert an inward pressure upon the mop as it is pressed downward toward the bottom. During this operation, the water is forced through the escape-openings both in the sides and in the 40 bottom.

As the structure is designed to be mounted on the side of a pail or bucket, obviously some attaching device must be provided for the purpose: In this instance, I prefer to 45 utilize that shown by way of example in the drawings. This comprises two or more bracket-elements 11, each suitably secured to the outside of the vessel and provided with a pendent portion 12 having one corner 50 slightly angulated to form a limiting stop 13. The portion 12 is spaced from the surface of the vessel so as to provide a clearance 14, clearly shown in Fig. 1. Pivoted on the pendent portion of the bracket is 55 a locking-piece 15 having a stop 15^a and a limiting-flange 16 on one edge and having its lower end extended beyond the extremity of the portion 12, said extremity being provided with a lug or projection 17 to facilitate 60 the movement of the piece 15. In use, the vessel 1 will be disposed within the bucket or pail A, say, and have its rear wall substantially perpendicular. The ring or bead 65 a on the bucket will then occupy a position in the upper part of the clearance 14, as

clearly shown in Fig. 2. In this instance, the bracket-portion 12 is on the outside of the bucket and, likewise, the locking-piece 15. This piece is provided with a curved upper end 18 which engages the bead or 75 ring a of the bucket. By this means, the vessel 1 is firmly clamped to the bucket and will remain so until the pivoted locking-piece 15 is raised to the position shown in Fig. 1, for instance.

An important advantage of my device is that it permits the use of any reasonable size of mop in it; that is, any up to the full size and capacity of the vessel. Moreover, by reason of the construction and the lines 80 upon which it is laid out, the center of the line of thrust—when the mop is pressed down into the vessel—is well within the pail; hence there is little or no danger of upsetting the pail.

From the foregoing, it will be perceived that I have devised a mop wringing structure which is well adapted to achieve the several objects and ends in view. The construction is simple and compact in form, is 90 particularly well suited for being mounted upon pails or buckets, and the parts of it are so formed as to permit of a ready and convenient application to such pails or buckets.

As many changes can be made in the above described construction and as many apparently widely different embodiments of the invention can be made without departing from the spirit thereof, it is intended 100 that all matter contained in the foregoing description and shown in the accompanying drawings shall be interpreted as illustrative and not in a limiting sense.

What I claim is:

1. A mop press comprising an integral structure having a front, a rear and bottom section, all formed in one piece, and each provided with apertures; the front and rear sections being inclined away from each other and at a slight inclination away from a vertical line to effect a wedging engagement between said section and a mop; and end portions connecting said sections.

2. A mop press comprising an integral structure having front, bottom and rear sections formed from a single piece of material and each provided with a plurality of apertures arranged therein to present a relatively smooth inner surface, and imperforate end portions connecting said sections; certain of the sections being approximately parallel and certain others of said sections being arranged at a slight inclination to a vertical line to effect a wedging engagement 120 between said sections and a mop.

3. A mop press comprising an integral structure having front, rear and bottom sections all formed from one piece of metal, and each provided with frusto-conical open-

ings the edges of which project beyond the outside surface of said sections, the inner surface of each of the sections being relatively smooth, end portions connecting said sections; certain of said sections being approximately parallel and certain others of said sections being arranged at a slight inclination away from a vertical line to effect a wedging engagement between said sections and a mop; said sections being at their upper

edges flared outwardly; and supporting instrumentality associated with certain of said sections.

In testimony whereof I affix my signature in presence of two witnesses.

ARTHUR L. LERCH.
